UNITED STATES PATENT OFFICE.

WILLIAM GREEN, OF BALTIMORE, MARYLAND.

WINDOW-BRACKET.

1,261,513.

Specification of Letters Patent.

Patented Apr. 2, 1918.

Application filed April 7, 1917. Serial No. 160,457.

To all whom it may concern:

Be it known that I, WILLIAM GREEN, a citizen of the United States, residing at Baltimore, in the State of Maryland, have 5 invented new and useful Improvements in Window-Brackets, of which the following is a specification.

This invention relates to a window bracket or self supporting means, and one object of 10 the same is to provide a device of this class that may be easily applied to window frames of various dimensions above a window sill and held in positively fixed applied position and also to include in the general structure means 15 whereby the shelf supporting parts may be adjusted to accommodate window sills of varying widths and also to compensate for inclinations of the upper surfaces of sills and maintain the shelf supported by the bracket 20 arms or members in true horizontal position. The improved window bracket is adapted to support various articles, such as window boxes, window gardens or other containing 25 devices, and at times parts of the bracket may be used as means for holding handled articles or containing devices.

The bracket is easily applied to any window frame and sill and the several parts may be readily constructed and associated.

30 The invention consists in the construction and arrangement of the several parts which will be more fully hereinafter described and claimed.

In the drawings:

35 Figure 1 is a perspective view of a bracket embodying the features of the invention and having the shelf or rest board disposed thereon in dotted lines.

40 Fig. 2 is a front elevation of the improved bracket shown applied, a portion of the bracket being broken away and shown in section.

45 Fig. 3 is a sectional end elevation of the improved bracket shown applied and illustrating the main attaching member and the sill or ledge engaging portions of the bracket shown in transverse vertical section.

50 Fig. 4 is a top plan view of one extremity of the improved bracket.

55 Fig. 5 is a bottom plan view of a portion of the bracket showing the depending sill or ledge engaging member in section.

Fig. 6 is a transverse vertical section taken in the plane of the line 6—6, Fig. 3.

55 Fig. 7 is a longitudinal vertical section on an enlarged scale through one extremity of

the main attaching member and showing a portion of the window frame also in section.

The improved window bracket embodies essentially a main attaching member 5, two connecting arms 6, two supporting and retention arms 7, and two extension arms 8. The attaching member 5 comprises a metal tube 9 open at opposite ends and having securing rods 10 movably mounted therein and projected from opposite ends thereof. The outer terminals of the rods 10 are formed with heads 11 provided with teeth or serrations 12, and extending longitudinally into each head and in central relation thereto is a socket 13. The inner ends of the rods 10 are reduced, as at 14, and thereover are fitted the opposite ends of a coiled spring 15 mounted in the tube 9, as shown by Fig. 2, and retained in central position by a pin 16 extending transversely through the tube and the spring and which operates to prevent the spring from shifting either to the right or left or from a predetermined applied position. The spring 15 exerts considerable tension on the rods 10 and operates to force the said rods outwardly. The heads 11 co-operate with studs 17, as clearly shown by Fig. 7, each stud being tubular and having a flanged base 18 with a serrated or toothed face 19 to engage the wood of the side of the window frame, each stud being fixed to the window frame by a screw 20 inserted therethrough. When the screws 20 are inserted through the studs 17 the serrated or toothed faces 19 of the bases 18 are brought into firm engagement with the window frame sides and the studs are thereby prevented from turning or shifting out of applied position. The serrations or teeth 12 of the heads 11 of the rods 10 engage the inner faces of the bases 18 and the attaching member 5 as a whole is thus prevented from rotating on the studs.

The connecting arms 6 each have a flat extremity 21 which is inserted through a slot 22 in the rod 10 near the outer end of the latter and is held in fixed position relatively to said rod by a set-screw 23. The arms 6 are similarly associated with and adjustable in the rods 10 without in the least interfering with the movement of the rods 10 in adjusting the attaching member 5 relatively to various widths of window frames, and the said attaching member 5 may be readily separated from the connecting arms 6 by releasing the set-screws 23 when it is desired

to arrange the parts of the bracket in compact form. Each connecting arm 6 also has a vertically disposed hanger 26 intersecting the attaching extremity 21 at a right angle, 5 and from the lower portion of the said hanger 26 a horizontal member 27 extends outwardly and intersects the hanger at a point slightly above the lower edge of the latter so that a stop or abutment 28 is provided below the 10 arm 27. The arm 27 near its outer end has a T-headed pin 29 secured therein with the T-head 30 at the lower end, as shown by Fig. 6, the said pin 29 adjustably engaging a longitudinal slot 31 in a horizontal member 15 32 of the supporting or retention arm 7, said arm 32 being of such thickness as to have its lower face flush with the lower edge of the stop or abutment 28. The arm 32 also has an outer shoulder or abutment 33 with which 20 the outer end of the arm 27 engages when each supporting or retention arm 7 is closed in relatively to the horizontal arm 27 of each connecting arm 6. Each supporting or retention arm 7 also has a depending arm 34 25 intersecting the arm 32 at right angles, the arm 34 serving to engage over and bear against the outer face or edge of a sill or ledge of a brick wall which may vary in accordance with building structures. The arm 30 32 with the arm 34 may be readily adjusted on the arm 27, the pin 29 sliding in the slot 31, and to separably associate the arms 27 and 32 the slot 31 has an inner enlarged extremity 35 which is large enough to permit 35 the clearance of the head 30 of the pin 29 therefrom. To prevent displacement of the arm 32 and its correlative arm 34 the said arm 32 has upwardly projecting side lugs 36 which engage the opposite edges of the arm 40 27, and by this means the said arm 32 will be prevented from shifting sidewise in relation to the arm 27.

The extension arms 8 are adjustably held by the depending arms 34 of the supporting 45 and retention arms or members 7, and each arm 34 has a segment 37 projecting outwardly therefrom. Each segment 37 is suitably secured to the arm 34 and is provided with notches 38 in its outer edge which are 50 adapted to be movably engaged by a pin 39 secured to and projecting from an inner angular head 40 formed as a part of each extension arm 8. Adjacent to the pin 39 the head 40 is also formed with an elongated slot 55 41 extending transversely thereof and engaged by a clamping screw 42 which extends into the segment 37 and by means of which the extension arm may be loosened and shifted so as to change the position of the 60 pin 39 relatively to the notches 38 and whereby each extension arm 8 may be adjusted relatively to a horizontal plane to compensate for inclinations of the upper surface of the window sill or ledge upon which the arms 32 65 and 27 are disposed and thereby provide for

a horizontal support of a shelf 43, as shown by dotted lines. The outer end of each arm 8 has an upwardly projecting stop or guard 44 to bear against the outer edge of the shelf 43. It will be seen that the width of the 70 shelf 43 will depend upon the width of the sill or ledge on which the arms 32 and 27 are disposed, the parts as shown in Figs. 1 and 3, for instance, having a minimum adjustment 75 or being fully contracted. When the arms 32 80 are adjusted or shifted outwardly relatively to the arms 27 to compensate for varying widths of window sills or ledges the extension arms 8 move equally in an outward direction and as a consequence the distance between the vertical members 26 of the connecting arms 6 and the guards 44 of the extension arms will be greater and a larger shelf may be disposed thereon or the same shelf may be used in all cases and the outer edge thereof 85 pushed out into engagement with the guards 44. The depending or vertical arms 34 of the supporting and retention arms 7 bear against the outer edges or faces of the window sill or ledge and materially brace the 90 structure, and particularly the extension arms 8, and permit considerable weight to be imposed on the outer part of the shelf 43 engaging the said arms. The adjustable features of the several parts of the bracket 95 which are utilized directly for supporting the shelf 43 make it possible to provide for a shelf of considerable width, with advantages in window bracket constructions, as more area or space is provided upon which 100 to dispose containing or other articles. At any time desired the shelf 43 may be removed and under such conditions the extension arms 8 may be adjusted so as to depend from the segments 37, and the lower edges 105 45 of the heads 40 may be brought to bear against the outer surfaces of the depending or vertical arms 34 and be held fixed by the clamping screws 42, and under this adjustment of the extension arms the guards 44 110 115 may serve as hooks upon which the bails or handles of buckets, baskets and other articles may be applied.

All the parts of the improved bracket are constructed of suitable metal and may be treated to render the same non-corrosive, and owing to the simplicity of the connections between the parts they may be readily detached or assembled and may also be economically manufactured and sold at a comparatively small cost. The improved bracket will be found exceptionally useful and advantageous, and it will be understood that it is intended to be applied not only to windows, but to other structures where it may be 120 found applicable and where a shelf may be needed.

What is claimed is:

1. In a window bracket, the combination of an attaching means to engage a window 130

frame or the like, and shelf holding means connected to the said attaching means and comprising angular connecting arms and supporting and retention arms adjustable in relation to the said connecting arms, the supporting and retention arms carrying adjustable extension arms.

2. In a window bracket, the combination of an attaching means to engage a window frame or the like, angular connecting arms applied near opposite extremities of the attaching means, angular supporting and retention arms adjustably engaging parts of the connecting arms, and extension arms carried by the supporting and retention arms and adjustable at an angle relatively to a horizontal plane, the said arms serving to hold a shelf in horizontal position.

3. In a window bracket, an attaching means for engagement with opposite portions of a window frame or the like, angle arms projecting from near the opposite ends of the attaching means, parts of the said arms being provided with notched segments, and extension arms pivotally held by the said segments and having means to engage the notches of the latter whereby the extension arms may be adjusted relatively to a horizontal plane in the arc of a circle, the said arms serving to support a shelf in a horizontal plane.

4. In a window bracket, the combination of an attaching means to engage a window frame or the like, and shelf holding means connected to the said attaching means and comprising angular connecting arms and supporting and retention arms adjustable in relation to the said connecting arms, a part of the connecting arms having headed pins and a part of the supporting and retention arms provided with slcts to adjustably receive the said pins whereby these arms may be adjusted to accommodate different widths of sills or ledges, the supporting and retention arms carrying adjustable extension arms.

5. In a window bracket, the combination of an attaching means consisting of a tubu-

lar member having a spring mounted therein, rods movably projectable from opposite ends of the tubular member, the inner ends of the rods engaging the spring and their outer ends provided with sockets, studs for securement to opposite sides of a window frame or the like in position to enter the said sockets, and shelf supporting means projecting outwardly from the said attaching means near the opposite ends of the latter.

6. In a window bracket, the combination of an attaching means consisting of a tubular member having a spring mounted therein, rods movably projectable from opposite ends of the tubular member, the inner ends of the rods engaging the spring and their outer ends formed with heads having serrated faces and central longitudinally extending sockets, studs for securement to opposite sides of a window frame or the like to engage in the said sockets, the studs having bases with serrated faces to engage the opposite portions of a window frame or the like, and shelf supporting means projecting outwardly from the said attaching means near the opposite ends of the latter.

7. In a window bracket, the combination of an attaching means to engage a window frame or the like, and shelf holding means connected to the said attaching means and comprising angular connecting arms and angular supporting and retention arms, the connecting and supporting and retention arms having horizontal members in superposed relation and slidably adjustable to accommodate the said arms to window sills or ledges of different widths, the supporting and retention arms also having depending members to bear against the outer edge of a sill or ledge, the supporting and retention arms carrying adjustable extension arms.

In testimony whereof I have hereunto set my hand in presence of two subscribing witnesses.

WILLIAM GREEN.
